COLLAPSIBLE TUBE CONTAINER

Heinrich Quittner, Vienna, Austria, assignor to
the firm Löwit & Comp., Vienna, AustriaApplication February 1, 1937, Serial No. 123,498
In Austria February 21, 1936

1 Claim. (Cl. 93—39.1)

This invention relates to collapsible tube containers made from paper. Tubes of this description made from paper are not suitable for the majority of purposes on account of their 5 poor resistance to mechanical and chemical strains, and are therefore precluded from most uses. In accordance with the present invention, however, tubes of this type can be rendered suitable for all purposes by providing 10 them on the inside with a film-like coating of elastic yielding material, such as rubber or the like. A film of the required nature is preferably produced by the coagulation of latex in a natural, dilute, concentrated, preserved, or vulcanized 15 condition. In this manner it proves possible to render the tube jacket fit to withstand all the strains to which it is subjected in use (drawing, squeezing, rolling, folding, and the like) without becoming injured.

20 By the provision of a film-like lining the tube wall is also rendered highly resistant to chemical attacks of all kinds, since rubber or the like is not attacked by the substances normally packed in collapsible tube containers, such as 25 aqueous emulsions, acids, alkalies, soaps, and the like. A film-like lining of the kind provided by the present invention also has the effect of completely sealing up all joints and crevices which result inevitably from the process of manufacturing 30 the tube, and the contents of the tube are consequently saved from the access of air and from becoming dry.

If desired, the tube may also be given an outside coating of moisture-repelling character, for 35 example a coating of varnish or the like, or enamel paint, and in this manner rendered proof against attacks of outside influences.

The paper tubes envisaged by the present invention may be manufactured by methods known 40 per se, it being preferable in accordance with the invention to employ, as adhesive for the paper in such manufacturing, yielding and elastic material such as rubber solutions, rubber emulsions, rubber dispersions, or the like, and preferably 45 latex or the like. In this manner the stuck joints and seams are rendered elastic and less liable to become damaged or leaky, as compared with the stiffness of the stuck surfaces and seams when glue, paste, or the like is used as 50 adhesive for the described purpose.

In the drawing, Fig. 1 shows a cross section of a tube stock which may be used in carrying out the invention; Fig. 2 illustrates a partially formed end closure in section; Fig. 3 shows in 55 elevation a suitable closure cap and its threaded

fitting; Fig. 4 shows in section the completed end structure of a collapsible tube produced according to the invention.

Tubes in accordance with the invention may conveniently be manufactured by rolling or winding adhesive-covered paper to form a tube, in such a manner that the wall thickness of the resulting tube is at least twice the thickness of the paper used. The tube can then be relied on not to burst even when the pressure set up 10 by squeezing is relatively great. A paper tube 1 (Fig. 1) of this description stuck together with latex or the like, which may be manufactured in any desired lengths and cut up into pieces of the length required to form a collapsible tube 15 container, is then upset at one end (for instance on a mandrel), and on the upset marginal portion 2 discs 3 and 4 (Fig. 2) are then placed on the inside and on the outside, the disk lying outermost in the finished tube being made preferably of metal foil. The best method to adopt 20 is to first apply the inner disc 3 to the mandrel, then to fit the paper tube thereover, and finally to apply the outer disc 4, after which the in-turned portion of the tube is united to the two 25 discs by means of an adhesive, preferably latex, under the application of pressure and heat. Into the tubular piece thus produced there is then inserted a disc-shaped member 5 of composition 30 (for instance bakelite or the like) or metal comprising the screw threading for the closure cap 7, in such a manner that the threaded extension 6 of this member 5 projects out of the tube 35 (Fig. 4). The tube thus formed, which is open at the one end, is then provided with a film-like 40 lining of latex or the like, for instance by pouring elastic yielding material, preferably latex or the like, through the tube after rendering the latter open at both ends by removal of the screw cap, with the result that a film 8 (Fig. 4) becomes formed on the inside of the tube wall, thus completely sealing the inside of the tube 45 and all the joints therein.

A film such as the film 8 produced in the described manner clearly differs from an ordinary impregnation in that it does also admit of detachment from the paper wall of the tube, whereas the usual impregnating agents such as paraffin, linseed oil, and the like penetrate into the paper fibres. Like a rubber tube, this film 50 can be subjected to very considerable strains without becoming injured, and is also resistant to chemical attacks to which rubber is by its nature proof. By its ability to follow every movement the film also forms an elastic rein- 55

forcement of the tube and enhances its softness and suppleness.

The open end of the tube may be closed in the known manner by folding or the like.

5 The finished tube may also be waterproofed on the outside by the application of a suitable coating.

Tubes manufactured in the described manner not only provide a fully equivalent substitute 10 for metal collapsible tube containers, but may also be used in cases in which metal tubes may not be used on account of their chemical and other properties.

The use of paper instead of the commonly 15 used metals, such as more particularly tin, also enables the manufacturing of the tubes to be very considerably cheapened.

I claim:

A process for the manufacturing of a collapsible tube consisting of forming a tubular body of paper, reducing the diameter of the body at one end, applying reinforcing members to 5 the inner and outer surfaces of the reduced portion of the body, fixing an outlet element to the reinforced end of the body and applying a coating on the inner surface of the body in the form of a film-like lining of an elastically 10 yielding material capable of being subjected to chemical and mechanical strains independently of the paper body.
